UNITED STATES PATENT OFFICE.

JOHN J. CARTER, OF ANDERSON, INDIANA, ASSIGNOR TO GENERAL MOTORS CORPORATION, A CORPORATION OF DELAWARE.

COMMUTATOR-SLOTTING APPARATUS.

Application filed October 31, 1923. Serial No. 672,008.

To all whom it may concern:

Be it known that I, JOHN J. CARTER, a citizen of the United States of America, residing at Anderson, county of Madison, 5 State of Indiana, have invented certain new and useful Improvements in Commutator-Slotting Apparatus, of which the following is a full, clear, and exact description.

This invention relates to the manufacture 10 of commutators for dynamo-electric machines, and particularly the type of commutator which includes a riser portion projecting radially from the brush contacting portion of each commutator segment, said 15 riser portion providing a connection between an armature conductor and the commutator segment.

It has been the practice to form a slot in 20 each of the commutator risers for receiving the ends of armature windings which are secured in position by soldering. The slotting operation is generally performed before the commutator is assembled on the 25 armature shaft. It is one of the objects of the present invention to reduce the cost of manufacture of such commutators, and therefore, the invention consists in providing mechanism for slotting all of the commutator risers simultaneously.

30 Other and further objects and advantages of the present invention will be apparent from the following description, reference being had to the accompanying drawings, wherein a preferred embodiment of one 35 form of the present invention is clearly shown.

In the drawings:

Fig. 1 is a plan view of the commutator fixture included in the present invention.

40 Fig. 2 is a sectional view on the line 2--2 of Fig. 1.

Figs. 3 and 4 are side and end views, respectively, of one of the spacing blocks included in the apparatus shown in Fig. 1.

45 Fig. 5 is a longitudinal sectional view of the apparatus showing one form of the invention, and

50 Fig. 6 is a plan view of a part for retaining in position the tools for cutting the slots in the risers.

In the drawings, 20 designates a plunger mounted preferably for vertical movement which is effected by means of a crank 21, 55 crank shaft 22, a pinion 23 attached to crank shaft 22 and meshing with a rack 24 at-

tached to the plunger 20. Plunger 20 is provided with a central recess 25 for receiving the shank 26 of a plate 27. A set screw 28 retains the shank 26 in position. To the plate 27 is secured by means of screws 29 60 and dowel pin 30, a retaining block 31 which includes a centrally disposed hub portion 32 from which radiate a plurality of wedge-shaped portions 33 spaced by radially extending notches 34. The block 31 is provided also with an annular groove 35 which intercepts each of the notches 34. Each notch 34 receives a broaching bar 36 having a back edge 37 parallel to the line of motion of the plunger 20, a plurality of broaching 70 teeth 38 progressively varying in distance from the back edge 37, and a beveled lower edge surface 39. The portion of each blade 36 which is included between the surface 39 and the teeth 38 is also beveled as indicated 75 at 40. As viewed in Fig. 5, the difference between the horizontal distance from the highest cutting tooth to the back edge 37 and the horizontal distance between the lowest cutting tooth 38 and the back edge 37, 80 will be equal to the depth of slot cut in the commutator riser.

The top edge 41 of bar 36 abuts the lower surface of plate 27. Each bar 36 is provided with a tang 42 which is received by 85 the annular groove 35. Each notch 34 of block 31 receives one of the broaching bars 36, there being as many bars as there are commutator risers to be slotted. The bars 36 are retained in position by set screws 43 90 carried by a retaining ring 44. To provide clearance for the end of set screws 43, the retaining block 31 is provided with a plurality of recesses 45 located adjacent each notch 34.

95 The bars 36 are identical except for one, namely, bar 36^a which is provided with an extension 46 which serves as a pilot and as means for locating the commutator indicated at 50 in Figs. 1 and 5. The commutator 50 may be any having risers extending from the brush engaging portion of the commutator segment, but for purposes of illustration, the commutator described and claimed in the patent to Oliver F. Conklin, Number 1,503,484, issued August 5, 1924, has been chosen. The commutator 50 includes a plurality of segments 51 clamped together by V-rings 52 and a clamping tube 53 having its ends 54 flared over the outer faces 100 105 110

of the V-rings. Each segment 51 includes two bars 55 and 56 which when assembled as shown in Fig. 1, provides a riser having a V-notch 57. In order that the riser may 5 be notched to receive the ends of armature conductors which are rectangular in cross section, it is desirable that the metal in the riser be cut away to change the V-notch to a rectangular notch.

10 The fixture which holds the commutator 50 while being operated upon and which guides the broaching bars 36 and 36^a, comprises a block 60 adapted to be secured preferably upon a horizontal support. The block 15 60 is provided with an aperture 61 in alignment with the block 31. From the aperture 61 there radiates a plurality of notches 62 located in alignment respectively with the several broaching blades 36. The block 60 20 is provided with a recess concentric with the aperture 61. This recess includes an annular groove 63, and receives a plurality of guide blocks 64 which are spaced by blocks 65, each block having a tang 66 received by the annular groove 63. The blocks 65 are located 25 in radial alignment with the notches 62, and the blocks 64 are located by dowel pins 67 and are secured by screws 68. The side edges of that portion of the upper surface 30 of each block 64 which extends between notches 62 is chamfered as indicated at 69 in Figs. 1, 3, and 4. The blocks 65 are as thick as the width of the notches 62. Since these blocks are in radial alignment with notches 62, each block 64 will include a portion which is in vertical alignment with a portion 70 of the block 60 which is included between adjacent notches 62. There are as many blocks 64 as there are bars 36. 35 Therefore, there will be a space between adjacent blocks 64 for receiving each broaching bar. In this manner, the broaching bars are guided through the work.

40 Preferably, the uppermost position of the plunger 20 is such that the extension 46 of bar 36^a will still project between two of the blocks 64 as shown in Fig. 5. A commutator to be slotted is located upon the fixture as shown in Figs. 5 and 1, with its main 45 or brush engaging portion disposed between the ends of the blocks 64 and its riser portions resting upon said blocks 64. One of the notches 57 is disposed so as to be received by the extension 46. Consequently, the other 50 V-notches 57 will be located in alignment with the notches 62 and spaces between the blocks 64.

55 The means for preventing endwise movement of the commutator in one direction includes two clamping devices, each comprising a slidable bar 80 having a clamping end 81 which is notched to receive one of the broaching bars 36. The bar 80 is slidable along a grooved block 82 secured to the base 60 block 60 by screws 83. A stud 84 threaded

65 tightly into the block 60 extends through a hole 85 in block 82, a coil spring 86, a washer 87 and an elongated hole 88 in block 80. The threaded upper end 89 of stud 84 receives a nut 90. The movement of nut 90 70 is limited by a pin 91 attached to the bar 80 and projecting into an arcuate groove 92 in the nut 90. The groove 92 is intercepted by a radially extending groove 93 connecting groove 92 with the threaded aperture in nut 75 90. When the bar 80 is in the position shown in the drawings and the nut 90 is turned clockwise as viewed in Fig. 1, portion 81 of the bar 80 will be clamped against the commutator. When the nut 90 is turned counter clockwise, the clamping bar 80 will be released and the spring 86 will cause the portion 81 to be separated from the commutator. The formation of the groove 93 provides a camming surface 94 which will engage the pin 91 when the nut 90 is turned counter clockwise and cause the bar 80 to be withdrawn from the commutator so that the commutator may be removed from the fixture. Obviously turning the nut clockwise 85 will cause the bar 80 to move toward the commutator into the position shown in Fig. 5, and further turning of the nut clockwise 90 will cause the bar 80 to be clamped 95 against the commutator.

95 Turning the crank 21 counter clockwise as viewed in Fig. 5, will cause the plunger 20 to descend and force the broaching bars into the V-notches 57 of the commutator 100 risers. Bars 36 are guided by the blocks 64 105 so that lateral movement is prevented. The result is that the broaching bars which cut away the material of the risers adjacent the notch 57 provide a notch of rectangular shape. Turning the crank 21 clockwise causes the bars 36 to be withdrawn from the fixture so that the commutator may be removed after the clamping bars 80 have been withdrawn sidewise.

110 The mechanism disclosed for operating the plunger 20 is only illustrative, and it is to be understood that any suitable power-driven mechanism may be employed if desired.

115 It is to be understood also, that the mechanism illustrated is applicable to commutators other than that shown in the drawings. The broaching bars are capable of cutting slots in commutator risers which are not provided with slots previous to the slotting 120 operation.

125 While the form of embodiment of the invention as herein disclosed, constitutes a preferred form, it is to be understood that other forms might be adopted, all coming within the scope of the claims which follow:

130 What is claimed is as follows:

1. Commutator slotting apparatus comprising in combination, a plurality of tools each adopted to slot a commutator segment,

- a tool holder adapted to be connected with said tools and maintain them in spaced relation, a work holder including a clamping member having a portion movable laterally 5 toward the commutator and movable longitudinally thereof to clamp the commutator in position, and a common operating member for moving said clamping member in both directions.
- 10 2. Commutator slotting apparatus comprising in combination, a plurality of tools, each adapted to slot a commutator segment, a tool holder adapted to be connected with said tools and maintain them in spaced relation, 15 a work holder for maintaining said commutator in position, said work holder including a clamp having a portion movable laterally and longitudinally with respect to the commutator, and a rotatable screw-threaded member for causing said clamp to move longitudinally to clamp the commutator, said screw-threaded member and clamp having cooperating provisions whereby partial rotation of said member will cause said clamp to move longitudinally 20 with respect to the commutator and further rotation causes the clamp to move laterally with respect to the commutator.

In testimony whereof I hereto affix my signature.

JOHN J. CARTER.
